UNITED STATES PATENT OFFICE.

CHARLES M. BURTON AND RIO GARDNER, OF NEW YORK, N. Y.

ROTARY ENGINE.

1,090,021.

Specification of Letters Patent. Patented Mar. 10, 1914.

Application filed October 26, 1912. Serial No. 727,953.

To all whom it may concern:

Be it known that we, CHARLES M. BURTON and RIO GARDNER, citizens of the United States, residing at New York, in the county of New York and State of New York, have invented certain new and useful Improvements in Rotary Engines, of which the following is a specification.

This invention relates to improvements in rotary engines of the internal combustion type.

Among the objects in view are the increasing of efficiency, the effective scavaging, and the maintenance of uniformity in the delivery of power.

With these and further objects in view, as will in part become obvious and in part hereinafter be stated, the invention comprises a rotary piston and means for subjecting the same to the expansive force of a succession of exploded charges during the course of a single revolution.

The invention also comprises the combination with a piston chamber, of a rotary piston therein, valved intakes for the piston chamber, open exhausts therefor, and radially movable blades carried by the piston in position for moving successively past a plurality of intakes and exhausts during a single revolution of the piston.

The invention further comprises a housing forming a piston chamber, a piston sustained by the housing and rotatably mounted in the chamber, an intake for the chamber adapted to receive an explosive charge under pressure, a valve controlling said intake, ignition means for such charge adjacent the intake, an open exhaust spaced from the intake, and a blade movably carried by the piston and adapted to move with the piston past the intake for being subjected to expansive pressure of an exploded charge and subsequently move past the exhaust.

The invention still further comprises certain other constructions, combinations, and arrangement of parts, as will in part become obvious and in part hereinafter be set forth in detail.

In the accompanying drawing: Figure 1 is a view in side elevation of an engine embodying the features of the present invention. Fig. 2, is a top plan view thereof. Fig. 3 is a vertical central section therethrough, parts being seen in elevation. Fig. 4 is an enlarged detail fragmentary sectional view taken on the plane indicated by line

4-4 of Fig. 3. Figs. 5 and 6 are fragmentary sectional views of the intake valve parts, parts being broken away and parts being seen in elevation.

Referring to the drawings by numerals, 1 indicates a casing or housing preferably surrounded by a water jacket 2 and mounted on a suitable stand or base 3. The ends of housing 1 preferably consist of detachable head plates 4, 4 bolted or otherwise suitably fixed to the body of the housing 1. Housing 1 is formed with an internal cylindrical piston chamber 5 within which is disposed a rotary piston 6 mounted on and keyed to the power shaft 7, which shaft extends through and finds bearings in the heads 4. Each head 4 is preferably formed with an outstanding bearing sleeve 8 containing ball or other suitable anti-friction bearings 9 for the journal portions of shaft 7.

At substantially opposite sides of the piston chamber 5 of housing 1 are formed circumferentially extending recesses 10, 10 disposed laterally with respect to the chamber and being arranged at one side of a diametrically opposite position so that the recesses 10 approach each other more closely at one side of the chamber 5 than at the other side thereof, which enables and facilitates firing of charges in the recesses 10 successively with respect to different parts of the piston, as hereinafter fully set forth.

An intake 11 is provided for each of the recesses 10 and is adapted to be supplied with an explosive fluid under pressure from a supply tube 12, a firing chamber 13 being disposed just inside of the intake 11 and being adapted to communicate therewith through a valve opening 14 which opening is adapted to be closed by valves 15, 15 each fixed on a rock shaft 16, shafts 16 extending laterally through the material of the housing, that is, through the side wall of the intake and of the firing chamber, the valves 15 being disposed at opposite sides of the recess 14 and adapted to be rocked to and from position closing the valve opening 14. Each shaft 16 is journaled in the wall of the housing and adapted to be rocked for affording the requisite movement of the valves 15, and to this end the outer end of each shaft 16 is provided with a crank arm 17 extending toward the other shaft, the arm 17 of each pair of shafts 16 having their adjacent ends lapping and connected by a pivot pin 18 which in turn is engaged by the bifur-

cated end of an actuating plunger 19. Each plunger 19 is preferably cylindrical in form and extends through a guiding eye 20 fixed to and outstanding from one of the heads 4 of housing 1. Each plunger 19 is formed with laterally extending lugs 21 and a spring 22 is preferably coiled about the plunger 19 between the bracket or eye 20 and the lugs 21, in position for pressing the respective plunger toward a closed position for the valves 15. A washer 23 is disposed between the end of the spring 22 and the lug 21, and at the opposite side of the lugs 21 from that engaged by washer 23 said lugs 15 are engaged by the arms of the bifurcated end of a trip lever 24, each lever 24 being pivoted to the head 4 and extending radially inwardly from the respective plunger 19 toward the shaft 7. A wheel or disk 25 is keyed to shaft 7 and at its outer face is provided with outstanding lugs 26, 26 spaced about the disk proportionately to the positioning of coöperating parts of piston 6, as will hereinafter appear, the lugs 28 being 25 positioned to strike one of the trip levers 24, and the other trip lever being adapted to be struck by similar lugs 29, 29 similarly disposed at the inner face of the disk or wheel 25, the lugs 29 being preferably spaced 30 slightly in the rear of lugs 28 contemplating the lugs with respect to the direction of their movement, the said spacing being proportioned to the relative coöperative action of the other parts of the apparatus.

35 Each firing chamber 13 communicates with one of the recesses 10 at or adjacent to one end thereof, each end of each recess being tapered or inclined, and the opposite end of each recess 10 from that with which the firing chamber 13 communicates opens into an exhaust port 30, each exhaust port 30 being left entirely open and free for the exhaust of burnt gases.

The piston 6 is formed with a plurality, 40 preferably four, of outwardly opening, radial grooves or notches 31 disposed to receive and form guide ways for radially movable piston blades 32, each blade being pressed radially outwardly by springs 33, 45 each blade having along its outer edge a rearwardly directed, tapering projection 34 adapted to engage the inclined wall at the intake end of the respective recesses 10, the outer end of each blade 32 being beveled 50 or inclined inwardly in the rear of the projection 34 to correspond to the inclination of the exhaust end of the respective recesses 10 for affording a cam surface for causing the respective piston blades 32 to move radially inwardly as the same pass the exhaust.

A suitable spark plug or other ignition means 35 is disposed to extend into each of the firing chambers.

65 The ends of the several lugs 28, 29 and 31

the trip levers 24 are rounded in the direction of movement of the respective elements for facilitating the tripping action and in order to enable ready starting of the engine, each lever 24 is adapted to be engaged by a manually controlled operating device. Such manually controlled device may assume any of numerous embodiments, as for example the lever and link system illustrated in Fig. 1 in which the lever 35' is pivoted to one of the heads 4 and extends beyond the housing and is provided with a treadle 36 adapted to be engaged by the foot of the operator. At one side of the pivot of lever 35' a link 37 is pivoted thereto and at the opposite side of the pivot of said lever 35' is pivoted a link 38. Link 37 extends past a guide 39 to a point beneath the respective trip lever 24 in position for engaging the lever and elevating the same when the treadle 36 is depressed. The link 38 extends past a guide 40 and past the respective trip lever 24 and is formed with an outwardly extending or hooked portion 41 disposed to engage and trip the lever 24 when the treadle 36 is depressed.

From the foregoing it is believed that the operation of the illustrative embodiment of this invention will be apparent and may be stated as follows: The operator, when the parts are in a stationary condition, merely depresses the treadle 36 and releases the same, and then advances or retards the commutator (not shown) until he secures a spark in one of the firing chambers 13. In the act of depressing the treadle 36 the operator will have opened the valves to all the intakes and thus admitted a charge to each firing chamber, the incoming gas being supplied under sufficient pressure for affording the desired explosion, and upon releasing the treadle the resultant closing of the valves will have left the parts in condition for firing, followed by a continuous operation. The firing of a charge in any one of the chambers 13 causes the expansive force of the explosion to act upon the adjacent piston 32, forcing the same along the recess 10 until it passes exhaust 30 and thus allows the exhausting of the burnt gases there-through. It is obvious that just after the firing in one of the chambers 32 the charge in the other chamber will be fired, thus supplementing the pressure on the piston 6, and before the exhaust of the pressure of the second fired charge from the chamber 10 another piston blade will have arrived in position for being subjected to the pressure of a third exploded charge, and so on continuously, the piston 6 being subject constantly to the pressure of an exploded charge acting on one or more of the piston blades so that substantial uniformity in the driving of the shaft 7 is obtained, and it is perfectly obvious that while only two of the 120

5 recesses 10 with the requisite coöperating parts have been illustrated, any desired number may be provided within the possibility of the limits of the dimensions of the apparatus, and likewise the number of piston blades may be varied at will for attaining the highest degree of efficiency in any particular construction.

10 It will be observed that by the employment of a valve 15 at each side of the partition through which the opening 14 extends, the inner valve will serve to protect the outer valve against the destructive effect of successive explosions and the inner valve 15 will continue to serve in this capacity while the outer valve will constantly insure a perfect closing of the opening. The swinging or oscillatory movement of the valves is also obviously valuable in insuring the removal 20 of any excess carbon that may tend to deposit on the valves.

Having thus described the invention, what is claimed is:

1. In an internal explosion engine, the 25 combination, with a housing having a piston chamber, of a rotary piston mounted therein, a plurality of sets of blades carried by said piston, each of said blades being radially movable therein, and the blades of each set being disposed diametrically opposite each other, recesses formed in the housing in communication with the piston chamber and disposed for being adapted to be entered by the piston blades, the recesses being 30 of substantially the same length and being disposed nearer each other at one side of the chamber than at the other side thereof, intake openings being formed in the housing at points spaced circumferentially from diametrically opposite points, each of said intake openings communicating with one of the recesses, and means for firing explosive charges admitted through said intake openings, the housing being formed 35 with an exhaust port for each recess, and each recess being elongated circumferentially of the housing and having its intake at one end and its exhaust at the other.

2. In an internal combustion engine, the 50 combination, with a housing having a substantially cylindrical piston chamber, of a rotary piston mounted therein, the housing having circumferential recesses spaced at substantially opposite sides of the piston 55 but disposed relatively to one side of diametrically opposite points, so that the recesses are nearer each other at one side of the piston chamber than at the other, the recesses being of substantially the same length, 60 diametrically opposite piston blades radially movably carried by said piston and adapted to be moved into and out of said recesses, and means for delivering and firing explosive charges in position for acting 65 against said blades while in said recesses.

3. In an internal combustion engine, the 70 combination, with a housing having a substantially cylindrical piston chamber, of a rotary piston mounted therein, the housing having circumferential recesses spaced at substantially opposite sides of the piston but disposed relatively to one side of diametrically opposite points, so that the recesses are nearer each other at one side of the piston chamber than at the other, the recesses 75 being of substantially the same length, diametrically opposite piston blades radially movably carried by said piston and adapted to be moved into and out of said recesses, means for delivering and firing explosive 80 charges in position for acting against said blades while in said recesses, an intake for the explosive charge for each recess being at one end of the recess, and an exhaust being provided at the opposite end of the recess. 85

4. In an internal explosion engine, the 90 combination, with a housing having a piston chamber, of a rotary piston mounted therein, diametrically oppositely disposed, 95 radially movable blades carried by said piston, recesses formed in the housing in communication with the piston chamber and disposed for being adapted to be entered by the piston blades, the recesses being of substantially the same length, intake openings being formed in the housing at points spaced circumferentially from diametrically opposite points, each of said intakes communicating with one of the recesses, and 100 means for firing explosive charges admitted to said intakes, the housing being formed with an exhaust port for each recess.

5. In an internal explosion engine, the 105 combination, with a housing having a piston chamber, of a rotary piston mounted therein, diametrically oppositely disposed, 110 radially movable blades carried by said piston, recesses formed in the housing in communication with the piston chamber and disposed for being adapted to be entered by the piston blades, the recesses being of substantially the same length, intake openings being formed in the housing at points spaced circumferentially from diametrically opposite points, each of said intakes communicating with one of the recesses, and means for firing explosive charges admitted to said intakes, the housing being formed with an exhaust port for each recess, each recess 115 being elongated circumferentially of the housing and having an intake at one end and an exhaust at the other.

6. In an internal explosion engine, the 120 combination, with a housing having a piston chamber, of a piston mounted therein, an intake for explosive medium for actuating the piston, the intake having a valve opening; an oscillating valve at each side of the opening, rock shafts carrying said 125 130

valves, and means for rocking said rock shafts in timed relation to and with the movements of the piston for moving the valves synchronously to and from a position 5 closing said opening.

7. In an internal explosion engine, the combination, with a housing having a piston chamber, of a piston mounted therein, an intake for explosive medium for actuating the piston, the intake having a valve opening, an oscillating valve on each side of the opening, rock shafts carrying said valves, means for rocking said rock shafts in timed relation to movements of the piston 10 for moving the valves to and from a position closing said opening, crank arms connected to said rock shafts, a plunger pivotally connected with the crank arms, a spring pressing each plunger to a position for maintaining the valves in position for closing said opening, a trip arm adapted to press said plunger to position for moving said valves from the closed position, and trip means for actuating said trip arm in 15 timed relation to movements of the piston. 20

8. In an internal explosion engine, the

combination, with a housing having a piston chamber, of a piston mounted therein, an intake at each side of the housing for explosive medium for actuating the piston, 30 each intake having a valve opening, an oscillating valve at each side of each opening, rock shafts carrying said valves, crank arms connected to said rock shafts, plungers pivotally connected with the crank arms, a 35 spring pressing each plunger to a position for maintaining the respective valves in position for closing said openings, trip arms adapted to press said plungers to positions for moving said valves from the closed position, and trip means for actuating said trip arms in timed relation to movements of the piston. 40

In testimony whereof we affix our signatures in presence of two subscribing witnesses. 45
